UNITED STATES PATENT OFFICE.

CARL FREDERICH GROMANN, OF NEW YORK, N. Y.

FINGER-BOWL.

1,249,745.

Specification of Letters Patent. Patented Dec. 11, 1917.

Application filed January 15, 1916. Serial No. 72,200.

To all whom it may concern:

Be it known that I, CARL FREDERICH GROMANN, a citizen of the Empire of Germany, and resident of the borough of Manhattan, 5 in the county of New York and State of New York, have invented certain new and useful Improvements in Finger-Bowls, of which the following is a specification.

This invention relates to a finger bowl 10 attachment, the object of which is to prevent using water or other fluid in said bowl or receptacle which has been previously used. The organization of the invention comprises a disk which is detachably connected to the 15 inner wall of the receptacle. Means are provided which coact with an orifice in the disk which allow the water or other fluid to flow from one compartment of the device to the other, and where said means have been 20 used their positions indicate to the user that the water or other fluid has been used.

The accompanying drawings exemplify the invention and in which Figure 1 is a vertical axial cross-section of a finger bowl, 25 with the invention in part axial section and part in full lines; Fig. 2 shows a fragmentary plan view of the finger bowl and invention; Fig. 3 represents an enlarged fragmentary portion of Fig. 2 and Fig. 4 shows 30 a top plan view of some details.

The finger bowl is indicated at 20 and has fastened to the inner face of its side wall the supporting brackets 21. A disk 22 is supported on the brackets 21. The said 35 disk has formed therewith the annular recess 23 with the annular groove 24.

A follower ring 26 with the annular groove 27 is bolted to the disk 22 by means of the screws 28. A pliable packing ring 30 40 preferably of rubber is clamped in the said grooves 24 and 27 and bears watertight against the inner face of wall of the bowl 20. The disk 22 has an orifice 33 preferably in the vertical axial center thereof. An annular pliable packing ring 34 preferably of rubber bears up against the bottom face of the disk 22. A pair of clamping rings 35 and 36 are fastened to the disk 22 and hold the packing ring 34 in place. The said packing ring 34 with its clamping rings 35 and 45 36 are concentric with the orifice 33. A bracket 40 is fastened to the bottom face of the disk 22 and has hinged to it the trap door 41 which latter has formed therewith 50 the latch lug 42. A spring latch is shown

to comprise a spring 43 which carries the push button 44 and the latch hook 45. A stop bracket 50 is fastened to the lower face of the disk 22 and clamps to the latter one end of the spring 43. The said bracket has 60 formed therewith the protecting leg 52. A spring 53 has one end fastened to the bracket 40 and the other end bears on the trap door 41.

A flexible pusher cap 55 is fastened to the 65 disk 22 over the push button 44. A handle 56 is connected to the hinge brackets 57 which latter in turn are attached to the disk 22. The said disk 22 when in place in the finger bowl divides the latter into the clean 70 water compartment 58 and the soiled water compartment 59.

To prepare the invention for use water or any other fluid is introduced into the compartment 58, which water may then be used 75 in the regular way. When the user has finished with the finger bowl he presses down on the pusher cap 55, which forces down the push button 44, and thereby releases the latch hook 45 from the latch lug 80 42. By this means the trap door 41 is allowed to swing down and the water in the compartment 58 flows through the orifice 33 into the compartment 59. To fill the compartment 58 the disk 22 is removed 85 from the bowl by means of the handle 56 and the trap door 41 is swung and locked in its closed position. The finger bowl having been emptied of its soiled water the disk 22 is replaced in the finger bowl, the packing 90 ring 30 making a watertight joint between the said disk and the bowl.

Having described my invention what I desire to secure by Letters Patent and claim is:

1. In a receptacle of the character described the combination of a detachable disk having an orifice, means to make a watertight joint between the disk and the wall of the receptacle, a trap door for said disk and hinged below said orifice to close the 100 same, and a push button extending through said disk to open said trap door.

2. In a receptacle of the character described the combination of a detachable disk having an orifice, means to make a watertight joint between the disk and the wall of the receptacle, a trap door for said disk and hinged below said orifice to close the 105 same, a spring latch with one end fastened to said disk engaging and locking the trap 110 door.

door when in its closed position, a push button carried on the spring latch extending through said disk to enable the trap door to be unlocked from the disk.

5. 3. In a receptacle of the character described the combination of a detachable disk having an orifice, a trap door hinged to the lower face of said disk for said orifice, packing means between the orifice and trap door, 10 a spring latch with one end fastened to the lower face of said disk and maintaining the trap door in place when in its closed position, a push button on the spring latch extending through an opening in the said disk, 15 and a flexible pusher cap carried on the disk over said push button to enable the push button to be forced down by exerting pressure on said cap.

4. In a receptacle of the character described the combination of a detachable disk having an orifice, a trap door hinged to the 20

lower face of said disk for said orifice, packing means between the orifice and trap door, a spring latch with one end fastened to the lower face of said disk and maintaining the trap door in place when in its closed position, a push button on the spring latch extending through an opening in the said disk, 25 a flexible pusher cap carried on the disk over said push button to enable the push button to be forced down by exerting pressure on said cap, and a stop bracket extending from the lower face of said disk and under the spring latch to protect the latter.

Signed at the borough of Manhattan in 35 the county of New York and State of New York this 10th day of December, A. D. 1915.

CARL FREDERICH GROMANN.
